UNITED STATES PATENT OFFICE.

ALBERT E. WOODEN, OF WATERBURY, CONNECTICUT, ASSIGNOR TO WATERBURY MFG. CO., OF WATERBURY, CONNECTICUT, A CORPORATION.

VACUUM-BOTTLE.

1,282,514.

Specification of Letters Patent. Patented Oct. 22, 1918.

Application filed July 31, 1918. Serial No. 247,639.

To all whom it may concern:

Be it known that I, ALBERT E. WOODEN, a citizen of the United States, residing at Waterbury, in the county of New Haven and State of Connecticut, have invented a new and useful Improvement in Vacuum-Bottles; and I do hereby declare the following, when taken in connection with the accompanying drawings and the characters of reference marked thereon, to be a full, clear, and exact description of the same, and which said drawings constitute part of this application, and represent, in—

Figure 1 a broken view partly in side elevation, and partly in section, of a vacuum-bottle embodying my invention.

Fig. 2 a detached view in side elevation of the coupling-ring.

Fig. 3 a detached sectional view of the nested drinking cups.

Fig. 4 a detached view in side elevation of my improved converting-collar.

Fig. 5 a broken detached view in side elevation of the sheet-metal cap of the bottle-shell.

My invention relates to an improvement in vacuum bottles of the class in which a plurality of tapered drinking-cups are applied in nested form to the shell of the bottle so as to form a component part thereof, the object of my present invention being to provide means whereby a standard vacuum bottle may be converted into a bottle of the type described.

With these ends in view, my invention consists in a vacuum bottle converting-collar adapted to be applied to the neck of a standard bottle for the conversion thereof into a bottle of the type described.

In carrying out my invention as herein shown, I employ a converting collar having its upper and lower ends differentiated in diameter and both threaded, its smaller upper end 2 being adapted in internal diameter to be screwed over the threaded neck 3 of the domical shell-cap 4 which has its lower end formed with threads 6 to adapt it to be permanently screwed upon the threaded upper end of the sheet-metal bottle-shell 7.

The larger lower end 8 of the converting-collar is threaded and formed with a spread-

ing abutment-flange 9 which rests upon the cap 4 when the threaded upper end 2 of the collar is applied to the threads 3 of the cap. The said lower end of the collar is adapted in diameter to have screwed upon it the threaded lower end of a removable coupling-ring 10 the upper end of which has a knurled edge 11 and an inwardly turned gripping-edge 12 which latter engages with the upper face of the outwardly turned bead-like rim 13 of the outermost of the nested drinking-cups 14 of which there are three in the bottle shown, though the number may be varied within limits as desired. The cups having been nested as shown, the ring 10 is slipped down over them and screwed upon the threaded lower portion 8 of the converting-collar, whereby the cups as a nest of cups are secured in place and form a component part of the bottle-structure, the rim 13 of the lowermost cup 14 being drawn firmly down upon a horizontal bearing-shoulder 15 formed between the upper and lower ends 2 and 8 of the converting-ring constituting the characteristic feature of my invention. By providing such a nest of cups and their coupling-ring with a converting-collar adapted to fit the threaded neck of a standard vacuum bottle, I am enabled to convert the same into a bottle of the type in which a nest of cups forms a part of its structure.

I claim:

1. A vacuum-bottle converting-collar having its threaded upper and lower ends differentiated in diameter and separated by an abutment-shoulder, its smaller threaded upper end being adapted to fit the threaded neck of a standard vacuum bottle and its larger threaded lower end being adapted to receive the coupling-ring of a nest of drinking cups the lowermost of which bears upon the said abutment-shoulder.

2. As a new article of manufacture, a vacuum bottle having a sheet-metal shell provided at its upper end with a threaded neck, a nest of drinking cups each having an offsetting rim, a coupling-ring formed at its upper end with a gripping edge and having its lower end threaded, and a converting-collar having its upper and lower

ends threaded and differentiated in diameter and separated by an abutment-shoulder, its smaller threaded upper end being adapted to fit the threaded neck of the shell and 5 its larger threaded lower end being adapted to receive the threaded lower end of the coupling-ring.

In testimony whereof, I have signed this specification in the presence of two subscribing witnesses.

ALBERT E. WOODEN.

Witnesses:

JOHN S. NEAGLE,
A. C. RECKER.
